UNITED STATES PATENT OFFICE.

WILLIAM C. KITT, OF CINCINNATI, OHIO.

BOX.

1,345,784.

Specification of Letters Patent.

Patented July 6, 1920.

Application filed May 7, 1919. Serial No. 295,383.

To all whom it may concern:

Be it known that I, WILLIAM C. KITT, a citizen of the United States, residing at the city of Cincinnati, in the county of Hamilton and State of Ohio, have invented certain new and useful Improvements in Boxes, of which the following is a specification.

My invention relates to boxes, containers or cartons for holding articles of merchandise, or for holding fruits, nuts, vegetables and the like, which is of the "knock down" class, so that it may be readily shipped and it may be quickly set up and formed when it is to be used.

Its locking means are unique and efficient and may be employed with any form of box or container.

One of the salient features of my invention is to provide a box of this class which when formed or set up for use, will have a double bottom, which is formed by the locking end.

Another feature consists in forming a peculiar lock for the bottom of the box, so that when the box is set up, only one element of the lock will be visible on the inside.

Another feature of my invention consists in forming a bottom flap, which is not cut away or recessed, and to form side flaps which have no locking parts thereon which interlock with the bottom flap.

Other features of the invention and advantages of construction will readily become apparent from the following specification and claim.

In the accompanying drawing forming part of this specification:

Figure 1, is a plan view of the blank which forms the box and its locking parts,

Fig. 2, is a plan view of the blank at an edge, and in a "knock down" form, folded for shipment,

Fig. 3, is an isometric view of the box inverted, the locking flaps opened up ready for folding to form the complete box,

Fig. 4, is a plan view of the box opened up the bottom folded over into position and the other flaps extended and ready for folding, and

Fig. 5, is an isometric view of the finished box, ready for use.

While I may apply my invention to any kind of a box, container or carton, I have shown it, applied to and in the form of a berry or fruit box and will describe such a

construction specifically to demonstrate one form of my invention.

The body of the box, herein shown in the drawings, outside of the bottom, is made up of sides 1, 2, 3 and 4, the side 1, carrying the flap 5; these sides being divided by crease lines 6, 7, 8 and 9. The sides are widest at the top and become narrower toward the bottom to produce a basket formation.

In the present instance, I place on the sides 1 and 3 the flaps 10 and 12 respectively, divided by the crease lines 13 and 14. These flaps 10 and 12 have an inclined upper edge 15, which extends from the apex or top corner of the flap down to where said flap joins the side flap to which it is connected. Between the flaps 1 and 3, and on the flap 2, I join the triangular shaped flap 16, creased with flap 2 on line 17; this flap carries at its head a locking flap piece 18. To the flap 4, I join the bottom flap or piece 19 having a peculiar shaped slot 20 cut therein, and joined with said flap 4 by crease 21.

The boxes are shipped in the "knock down" form shown in Fig. 2, and when it is desired to use one of the boxes, it is quickly pressed into the form approximately shown in Fig. 3, then the bottom flap 19, which forms the bottom of the box is folded down on crease 21 into the position shown in Fig. 4, the side flaps 10 and 12 are then folded over onto the flap 19 bending on the creases 13 and 14; these flaps at their free corners overlapping, as shown by dotted lines in Fig. 4, the flap 16 is then bent down thereon bending at the crease 17 and the cap or locking button flap 18 is pressed through the slit 20 in the bottom flap 19; this locks all the parts in place so that a box is formed having an open top and a double bottom, which is smooth on the inside, only interrupted by the button flap 18 as shown in Fig. 5.

It will be noted that the bottom flap 19 forms one bottom and the flaps 10, 12 and 16 form the other bottom and thus a box is formed with a double bottom, the flap 19 forming a solid uninterrupted bottom which reinforces the box, so that no side pressure will mar or tend to impair the strength of the box.

This box and its locking parts may be made of any suitable material, preferably out of card board or paper and on account

of the simplicity of the locking device can be used on very small boxes, as flaps are formed in such a manner that they can be readily and quickly bent or folded, even if 5 very small, very quickly and rapidly and easily, and the button flap 18 can be inserted into the slit 20 without injuring or breaking the same as it readily finds its way into the slit 20 and also securely locks the parts 10 against displacement. It will be understood that the contour and shape of these flaps may be somewhat varied and modified and they may be used in connection with a box body of any description; either open at both 15 ends or closed at one end, although herein shown connected with a box body which is opened at the top.

I claim:—

20 A box composed of sides forming a body therefor, provided with a bottom flap,

shaped to form the bottom of the box and carrying a slit therein, two side flaps, each of said side flaps having a straight outside line and an inclined line running from the outer edge of said straight line down to the 25 point where the flap meets the body of the box, and a triangular shaped locking flap carrying a button at its outer extremity, said side flaps capable of being folded over onto the bottom flap and at their free ends 30 overlapping each other, and said locking flap and its button capable of being folded over onto the overlapped side flaps, its locking button engaging the slit in the bottom flap and passing therethrough to lock the parts 35 together.

In testimony whereof, I affix my signature at Cincinnati, Ohio, this sixth day of May, 1919.

WILLIAM C. KITT.
